UNITED STATES PATENT OFFICE.

HUGH C. FOSTER, OF KANSAS CITY, MISSOURI, ASSIGNOR OF ONE-HALF TO ADOLPH PUCKER, OF KANSAS CITY, MISSOURI.

INVISIBLE BELT COUPLING.

Application filed November 25, 1922. Serial No. 603,334.

To all whom it may concern:

Be it known that I, HUGH C. FOSTER, a citizen of the United States, residing at Kansas City, in the county of Jackson and State 5 of Missouri, have invented a new and useful Invisible Belt Coupling, of which the following is a specification.

My invention relates to invisible belt couplings, and the object of the invention is to 10 provide a belt coupling which shall be attached on the waist band of a pants to invisibly receive the conventional pants belt and permit the same to be used on the inner side of the waist band, thereby rendering 15 the belt and its couplings invisible when worn to hold the pants on the hips of the wearer, and leaving visible a name plate at the fly of the pants.

I attain these objects by means of the combination of parts illustrated in the accompanying drawing in which Figure 1, is a view of the reverse side of a belt and couplings embodying my invention; Figure 2, 20 is a view of the upper edge of the belt and couplings, and showing the same in operative position on fragmentary portions of the waist band of a pants; Figure 3, is a front view of a pants supportingly engaged by my invention, the name plate being broken 25 away to disclose the slot in the waist band of the pants, and Figure 4, is an end view of one of the couplings, taken on the line 30 4-4, in Figure 1.

Similar numerals of reference refer to 35 corresponding parts throughout the several views.

The numeral 1, designates a portion of the conventional pants worn by men and having the usual waist band 2, and a fly 3. The 40 invisible belt couplings embodying my invention comprises a name plate 4, which is adapted for displaying on the outside of the front of the pants, the plate being curved suitably to make the same conform substantially with the contour of the body of the wearer when the pants is worn. The name plate is provided with oppositely disposed lugs 5, at the side edges thereof and located intermediately of the ends of the plate, the 45 lugs being provided with pivot holes 6. A buckle member 7, having a plane portion 8, an inwardly extending portion 9, provided with a pin 10, upturned flanges 11, and down turned flanges 12, is pivotally mounted on 50 the name plate by pivots 13, which are ex-

tended through the lugs 5, on the plate and flanges 12, on the buckle member. Between the flanges 11, is pivotally mounted by pivots 14, a tongue 15, having a downwardly extending portion 16, having teeth or points 60 17, adapted for biting into a belt lodged thereunder in the buckle member. In the plane portion 8, are parallel slots like those shown at 18, in Figure 1, thus providing between the slots a portion, as shown at 19, 65 in Figure 1, to facilitate the sewing of the buckle member on the waist band of the pants. Placed in the buckle member 7, is the one end of a belt 20, which is held therein by the teeth of the tongue 15. The belt 70 is extended from the buckle member along the inner side of the waist band of the pants, through loops 21, to a little distance inwardly of and behind the plate 4, where it is passed outwardly of the waist band, 75 through a slot 22, therein, the end portion of the belt being entered into a buckle member 23, which is sewed on the outer side of the waist band and hidden by the plate 4, the member comprising a plane portion 24, 80 having side portions or flanges 25, in which flanges is pivotally mounted a tongue, not shown, but identical with the tongue 15, on the buckle member 7, and an inwardly extending portion 26, having a slotted aperture 27, therein, which extension is adapted for overlapping the extension 9, on the other buckle member, so that the slot therein shall engage the pin 10, and thereby hold the belt 85 ends properly coupled.

The conventional belt is worn on the outside of the pants and the couplings or buckles are constantly exposed to view. The belt and the buckles are not attached to the waist band of the pants, but the belt is held in 90 place by loops attached on the outside of the waist band, which arrangement does not prevent the belt from slipping around the body of the wearer and pulling the buckle to one side or the other of the fly front of the pants. The belt couplings of my invention are rigidly attached on the waist band of the pants and, therefore, when they are coupled the name plate is stationary at the fly front of the pants, and the belt being 95 wholly invisible, the pants presents a much neater appearance and is better adjusted to the body of the wearer. The belt may be made of elastic material, such as suspender fabric, and if the belt requires tightening, 100 105 110

the same may be drawn tighter and thereafter held by the buckles. The couplings may be attached on the waist band of the pants, at the factory, tailor shop, or may be attached to pants already in use. The wearer of the pants may select his own belts and use as many kinds as he may desire. The belt being arranged on the inner side of the waist band makes the adjustment thereof to the body of the wearer a pleasure and the non-movable character of the belt couplings is a source of comfort and pleasure, as the wearer will be conscious that he is neatly dressed.

15 Having described my invention what I claim is—

1. In an invisible belt for pants, the combination with the waist band of the pants, of a name plate disposed in front of the fly end portions of the waist band, a buckle member attached on the inner side of the overlapping fly end portion of the waist band and pivotally mounted on the inner side of said name plate, a buckle member attached on the outer side of the underlapped fly end portion of the waist band and detachably connected to said first mentioned member, a transverse slotted aperture in the underlapped fly end portion of the waist band rearwardly of said name plate, and a flexible elastic strip extending along the inner side of the waist band and through the aperture

therein and adjustably connected with said buckle members.

2. In an invisible belt for pants, the combination with the waist band of the pants, of a name plate displayed in front of the fly end portions of the waist band, a buckle member attached on the inner side of the overlapping fly end portion of the waist band and pivotally mounted on the inner side of said name plate, said buckle member having at its inner end an extension provided with a stop, a buckle member attached on the outer side of the underlapped fly end of the waist band, said last mentioned buckle member having at its inner end an extension provided with an elongated eye adapted for receiving therein the stop on said first mentioned buckle member to thereby couple said members, a transverse aperture in the underlapped fly end portion of the waist band located rearwardly of said name plate, and a flexible elastic strip adjustably connected between said buckle members and extending along the inner side of the waist band and through the aperture therein.

Kansas City, Missouri, November 17, 1922.

HUGH C. FOSTER.
